PIEZO-ELECTRIC CRYSTAL APPARATUS

Clarence W. Hansell, Rocky Point, N. Y., assignor
to Radio Corporation of America, a corporation
of Delaware

Application January 23, 1932, Serial No. 588,255

8 Claims. (Cl. 171—327)

This invention relates to piezo-electric crystal apparatus and has especial reference to the electrode structure thereof.

It is well known in the art that the free vibrations of a piezo-electric crystal element set up strains and stresses which are substantially proportional to the voltages applied thereto. These stresses in the crystal element are frequently unsymmetrical due to the non-uniformity of the thickness of the element and the presence of different electro-motive forces on adjacent portions of the crystal. This unsymmetry, it has been found, is an undesirable characteristic which should be avoided for best results, particularly so in systems wherein a plurality of electrodes are utilized on the same side of the crystal. In this case slight differences in the thickness at various points on a crystal, and varying piezo-electric properties of the material, tend to cause considerable variation in relative voltages set up on the electrodes. Accordingly, it is a desideratum that the electro-motive forces of each electrode be applied to the crystal over as wide an area as possible and that the areas used be variable in order that more uniform voltage ratios may be obtained with various individual crystals used with the same holder and electrodes or with holders and electrodes of the same design.

This is accomplished in the present invention by constructing the electrodes adjacent one face of the crystal element so that each electrode covers rather widely separated areas and each is unsymmetrical with respect to any one plane passing through the crystal. This unsymmetry of the electrodes is an important characteristic of the present invention. In this manner, the respective electrodes affect simultaneously widely separated points of the crystal and aid in securing a uniform piezo-electric coupling effect between the electrodes.

A feature of this invention is the rotatable electrode mounting employed for changing the relative areas of the crystal facing the electrodes. By means of this feature one may obtain a degree of adjustment by the use of unsymmetrical electrodes which is not possible of obtainment, so far as applicant is aware, by any other type of electrode structure.

This invention is described in more detail in the following description which is accompanied by drawing wherein:

Figure 1 illustrates a plan view of one particular embodiment of the present invention, showing a two-electrode structure adapted for use on one side of a piezo-electric crystal element.

Figure 1A is a cross-sectional view of the electrode assemblage of Figure 1 along the line A—A.

Figures 2 and 3 are plan views of other embodiments of the present invention.

Figures 4, 5 and 6 show mountings for the crystal element which may be used with the structure of Figures 1, 2 and 3.

Figure 7 shows diagrammatically a circuit arrangement wherein there is employed a piezo-electric crystal structure embodying the principles of the present invention.

In Figure 1 is shown an electrode mounting comprising two spirally wound, metallic electrodes 1 and 2 mounted on a suitable insulating disc 3 such as bakelite. These electrodes may be attached to the insulating disc 3 either by screws or by being molded therein. The surfaces of the two electrodes 1 and 2 differ in area at different portions thereof in the manner indicated in the drawing and are arranged to be unsymmetrical with respect to any plane passing through either the mounting or the crystal. In this manner each electrode presents a surface which faces widely separated portions of the crystal so that closely spaced points of the crystal at different parts thereof face different electrodes. It will thus be apparent that any rotation or movement either of the electrode mounting or the crystal will change the relative areas of the crystal facing the two spiral electrodes.

Figure 1A is a cross-sectional view of the electrode assemblage of Figure 1 along the line A—A and shows electrodes 1 and 2 mounted on insulating disc 3. Obviously, it is within the scope of the present invention to so arrange the electrodes that their top surfaces are level with the surface of the disc.

Figures 2 and 3 are modifications of the arrangement of Figure 1 and disclose other electrode structures embodying the principles of this invention. The electrodes of these figures are also arranged to be unsymmetrical with respect to any one plane. Although only two electrodes are shown in these figures it will be understood that, if desired, other electrodes may be mounted on the insulating disc in a similar manner.

Figures 4, 5 and 6 illustrate one type of lower electrode assemblage which may be used with the arrangements of Figures 1 to 3. The crystal element 4 shown in these figures is mounted on metallic electrode 6 of the solid circular type which, in turn, is mounted on an insulating plate 8. Figure 4 discloses one way of maintaining crystal element 4 in position. In this drawing members 7, 7 firmly secure crystal element 4 to

the electrode assemblage. These members may be attached to lower electrode 6 in any desired manner. Other positioning means such as brackets 5 shown in Figure 5 or pins 23 shown 5 in Figure 6 may advantageously be employed. Brackets 5 are slidably movable in grooves shown on the plates and are held fixed to the lower electrode by means of screws. It should be understood, of course, that Figures 4, 5 and 6 shown 10 herein are merely illustrative of any lower electrode assemblage which may be employed and form no part of the present invention.

In Figure 7 is shown an oscillation generator circuit of the type described claimed and shown 15 in Fig. 3 of the drawing in an application, Serial No. 531,684, filed by J. L. Finch, April 21, 1931, wherein this invention may be employed. In this circuit there is illustrated a vacuum tube oscillation generator 10 having the usual anode 20 electrode 11, grid 12 and filament 13 provided with the usual filament current supply source 14 and anode voltage supply source 15. Condenser 16 is provided to shunt the radio frequency currents in the anode circuit around the voltage source 25 15. Associated with anode 11 of the generator 10 is a plate impedance 17 connected to the output circuit. To this impedance is connected lead 19 which connects with spiral electrode 2 of the piezo-electric crystal apparatus. The grid 12 of 30 the generator 10 is shown connected to the other spiral electrode 1 of the apparatus. Both electrodes 1 and 2 are of the unsymmetrical type and are mounted on rotatable insulating disc 3. A portion of this disc and upper electrode assemblage has been shown cut away in order to provide a semi-sectional perspective view of the entire crystal apparatus. The upper electrode assemblage, including insulating disc 3, is supported on a ring 9 which provides proper spacing 40 between crystal 4, which is attached to lower electrode 6 by means of pins 20, and upper electrodes 1 and 2. It is to be understood that the spacing between the crystal element 4 and the upper electrodes shown in the drawing is greatly 45 exaggerated and is merely for the purpose of illustration since, in actual practice, the spacing would usually be from approximately one to three thousandths of an inch.

The operation of this circuit is as follows: 50 Voltage waves impressed on grid 12 of the tube 10 are amplified in the tube and are, in turn, impressed upon the resistor circuit 17 by anode 11. Energy is fed from the output circuit 19 and impressed on the electrode 2, setting up a voltage 55 between electrodes 2 and 6. If this energy is periodic and has components corresponding in frequency to some mode of mechanical vibration of the crystal member 4, it will set up oscillations in the crystal. Due to these oscillations and also 60 due to the piezo-electric properties of the crystal, voltages of this same frequency will be impressed upon electrodes 1 and 6. These voltages are introduced in the input circuit 18 which is arranged to impress voltage waves upon the grid 12 65 identical with those originally assumed. Thus, this circuit will sustain oscillations and, if other conditions are correct, will build up oscillations, from an initial non-oscillating state, at the frequency at or close to the resonant frequency of 70 the crystal. The output of this generator may be taken off by lead 21.

In this circuit one may obtain optimum operation of the circuit by moving the upper electrode assemblage of the crystal control apparatus 75 through rotatable member 3 to obtain the de-

sired relative voltages on the primary and secondary electrodes 1 and 2 for building up and sustaining oscillations in the circuit. Consequently, fewer crystals must be rejected and the uniformity of operating adjustments obtainable 80 helps to make the frequency of the oscillations less subject to influences tending to change the frequency.

It should be noted that, in the circuit of Figure 7, the piezo-electric crystal and its electrodes really constitute a filter between the anode and grid circuits which passes an extremely narrow band of frequencies and it is this filter action which prevents production of oscillations at a frequency much different from the natural period 90 of the crystal. This arrangement of variable unsymmetrical electrodes really serves to make variable the effective characteristic impedance inside the crystal filter and its effective relative 95 terminal impedances at its input and output ends.

It is to be understood that this invention is not limited to the precise arrangement of parts illustrated and described herein, but that many modifications of the crystal mounting and holder are possible without departing from the spirit 100 and scope of the invention. For example, if desired, an arrangement similar to Figures 1, 2 and 3 may be utilized for a lower electrode assemblage. Also, other configurations of the electrodes may be resorted to in order to give the 105 desired results, provided, of course, that the electrodes observe the important characteristic of being unsymmetrical with respect to any one plane.

What is claimed is:

1. An electrode mounting for a piezo-electric 110 crystal, comprising an insulating member, a plurality of electrodes positioned on the same side of said member and arranged unsymmetrically with respect to any one transverse plane passing through said crystal.

2. An electrode mounting for piezo-electric crystal apparatus, comprising a plurality of spirally wound electrodes affixed to an insulating plate and positioned on one side of said crystal, said electrodes being arranged unsymmetrically 120 with respect to any one transverse plane passing through said crystal structure.

3. In piezo-electric crystal apparatus, a piezo-electric crystal, a plurality of electrodes in electrical relation with said crystal, at least two of 125 said electrodes being on one side of said crystal and arranged unsymmetrically with respect to any transverse plane passing through said crystal.

4. A mounting for a piezo-electric element, 130 comprising, in combination, a piezo-electric crystal, two spirally wound metallic electrodes spacially positioned on the same side of said element and attached to an insulating member, said member being rotatably movable with respect to 135 said crystal.

5. In combination, in a piezo-electric crystal holder, an insulating electrode support, two E shaped metallic electrodes mounted on a single insulating element and separated from each 140 other, the projecting portions of each electrode being arranged to intermesh with corresponding portions of the other electrode.

6. A piezo-electric crystal holder comprising in combination a mounting for a piezo-electric 145 crystal element comprising, a crystal, a plurality of unsymmetrically arranged electrodes positioned on the one side of the crystal, said electrodes being rotatable with respect to said crystal.

7. A piezo-electric crystal controlled oscillator 150

mounted in a crystal holder with a plurality of electrodes on one side of the crystal which are unsymmetrical with respect to any one transverse plane passing through said crystal.

5 8. A piezo-electric crystal holder comprising an upper and a lower insulating member, a spacing ring interposed between said upper and lower member, said lower insulating member having an

electrode arranged to retain a piezo-electric crystal, said upper insulating member having a plurality of unsymmetrically arranged electrodes retained within the inside of said upper insulating member and adapted for rotation with respect to said lower member.
